UNITED STATES PATENT OFFICE.

ZACHARY T. FRENCH AND WILLIAM C. MEYER, OF BOSTON, MASSACHUSETTS.

ROUNDING AND CHANNELING MACHINE.

SPECIFICATION forming part of Letters Patent No. 630,338, dated August 8, 1899.

Application filed December 16, 1895. Serial No. 572,258. (No model.)

To all whom it may concern:

Be it known that we, ZACHARY T. FRENCH and WILLIAM C. MEYER, of Boston, county of Suffolk, State of Massachusetts, have invented

5 an Improvement in Rounding and Channeling Machines, of which the following description, in connection with the accompanying drawings, is a specification, like letters on the drawings representing like parts.

10 This invention relates to machines for rounding and channeling the soles of boots and shoes while upon the last, and has for its object to provide such a machine with a guiding device which is freely movable during the rounding and channeling operation to vary 15 the position of the boot or shoe with relation to the rounding and channeling knives, whereby the sole will be reduced to its finished size and the width of its projecting edge may be 20 varied, producing what is commonly called a "Scotch" edge.

The invention consists, essentially, in the combination of rounding and channeling knives, feeding mechanism comprising two members which receive between them the 25 projecting edge of the sole, and a guiding device for the boot or shoe, which is freely movable toward and from said rounding and channeling knives during the rounding and channeling operation to vary the position of the work with relation to said knives in order 30 that the width of the projecting sole may be varied. The guiding device may be made to enter and even bottom in the crease between the upper and welt, or it may be made to bear 35 against the upper drawn taut over the last adjacent the crease; but in either case it will be arranged to act upon the work opposite where the rounding is being done and will be 40 made tapering or pointed or quite thin, so as to serve properly as a work-gage or guiding device for the boot or shoe along the shank as well as around the fore part. The work-gage or guiding device is made to continuously engage the boot or shoe all around— 45 i. e., all around that portion which is to be rounded and channelled. The feeding mechanism may be made in many different ways, and for simplicity the feeding mechanism is 50 herein shown as consisting, essentially, of two members adapted to receive between them

the projecting edge of the sole and welt and to be operated to feed along the work. The rounding and channeling tools may be of any usual construction.

55

Figure 1 shows in side elevation a rounding and channeling machine embodying this invention; Fig. 2, a detail of the support for the upper feed-wheel and guide.

The main frame A is shaped to support the 60 working parts and is mounted upon the stand B. The shaft b has its bearings in said frame and has at one end a gear b', which is engaged by a pinion b², secured to a short shaft carrying a belt-pulley b³. A pinion b⁴ (see dotted 65 lines) is also secured to said shaft b and engages an intermediate pinion b⁵, which in turn engages a pinion b⁶, secured to a shaft carrying the lower member of the feeding mechanism, herein shown as a wheel.

70

c represents a channel-knife which is attached to the support c'.

The rounding-knife d is mounted upon a vibrating arm d', operated by any suitable mechanism. This knife rounds or trims the 75 edge of the sole.

e represents a guide, which is made more or less V-shaped, as desired, to enter the crease between the welt and upper or to bear against the upper drawn taut over the last. The particular form herein shown is adapted to enter the crease. This guide is herein shown as a wheel axially mounted upon the arm e', which is formed integral with or secured to the arm e'', pivoted at e³ to the upper end of one arm 80 of a bell-crank lever e⁴, pivoted at e⁵ to the frame, the other arm of said bell-crank lever being connected with a treadle-rod e⁶, which passes down through the frame to a treadle. (Not shown.) By depressing the treadle-rod 90 e⁶ the bell-crank lever will be turned on its pivot and the arm e² moved longitudinally, thereby moving the guide e in and out with relation to the channeling and rounding knives.

The guide e is located so as to act upon the boot or shoe directly opposite where the rounding is being done and not one side or the other of such point. This is particularly important in order that the shape of the sole shall 100 correspond with the shape of the bottom of the last, except where purposely varied.

95

In addition to the feed-wheel b^7 , which forms the lower member of the feeding mechanism, another feed-wheel is provided for the opposite side of the sole, and this upper member of the feeding mechanism is herein shown as formed on the under side of the guide e —that is to say, on the under side of this guide teeth are formed—and the guide being set obliquely said teeth at the point of contact or engagement with the work occupy substantially a horizontal position. This guide and feed-wheel is placed in a suitable support or holder f , which is cut away at f' to accommodate the rounding-knife as the guide is moved in and out. The support or holder f is attached to the forward part of the arm e^2 . Bevel-teeth f^2 are formed concentrically around the axis of the feed-wheel, which are engaged by a bevel-gear f^3 , secured to a shaft f^4 , having its bearings in the main frame, and to said shaft a toothed gear f^5 is secured, which is engaged by a toothed gear f^6 on the shaft b , so that by such driving mechanism the feed-wheel will be positively rotated.

The guide and feed-wheel are formed in one piece merely for the sake of simplicity.

The arm e^2 is pivoted at e^8 , so that it may be raised to admit the work. For the purpose of raising this arm a vertical rod or link n is connected to it, the lower end of which is connected to one end of a bell-crank lever n' , pivoted to the frame, the other arm of which has a long extension in the form of a handle n^2 , which may be operated when desired to raise the arm e^2 .

We are aware that a movable guide has been employed in combination with a channeling-knife for the purpose of so varying the location of the boot or shoe that the channel-slit may be cut more or less distant from the edge of the sole; but we are not aware that such a guide has ever been employed in combination with rounding and channeling knives, whereby the width of the projecting edge of the sole may be varied and the channel cut.

The guide herein shown, it will be seen, acts continuously all around the boot or shoe—that is to say, all around that portion thereof which it is desired to trim the edge of the sole and cut the channel—and the extent that it enters the crease depends entirely upon the shape that may be given to it. If the V-shaped edge of the guide is quite sharp, it will not only enter but bottom in the crease, and if made quite blunt it will bear more particularly upon the upper drawn taut over the last. The sole which is thus rounded is reduced to its finished size and to a desired shape along its shank portion as well as fore part.

The feeding mechanism herein shown, it will be seen, comprises, essentially, two members which act upon opposite sides of the sole, being held pressed together to clamp the sole and operated by suitable mechanism to feed along the work.

The arm e^2 is normally held pressed down by the spring m . (See dotted lines, Fig. 1.) Two adjustable limiting-stops o are provided for limiting the forward and rearward movement of the guide. 70

We claim—

1. In a machine for rounding and channeling the soles of boots and shoes while upon the last, the combination of rounding and channeling knives, feeding mechanism comprising two members which receive between them the work, and which are operated to feed along the work; and a guiding device for the work, movable freely toward and from the rounding and channeling knives during the rounding and channeling operation, to vary the position of the boot or shoe with relation to said knives, and thereby vary the width of the projecting edge of the sole, said guide being constructed and arranged to engage the work close to and directly opposite where the rounding is being done, substantially as described. 90

2. In a machine for rounding and channeling the soles of boots and shoes while upon the last, the combination of rounding and channeling knives and feeding mechanism, and a guiding device which is in continuous engagement with the boot or shoe, and which is movable freely toward and from the rounding and channeling knives during the rounding and channeling operation, to vary the position of the boot or shoe with relation to said knives, and thereby vary the width of the projecting edge of the sole, said guide being constructed and arranged to engage the work close to and directly opposite where the rounding is being done, substantially as described. 95

3. In a machine for rounding and channeling the soles of boots and shoes while upon the last, the combination of rounding and channeling knives and feeding mechanism, and a guiding device for the work shaped to enter the crease, and movable freely toward and from the rounding and channeling knives during the rounding and channeling operation, to vary the position of the boot or shoe with relation to said knives, and thereby vary the width of the projecting edge of the sole, said guide acting upon the work opposite where the rounding is being done, substantially as described. 105

4. In a machine for rounding and channeling the soles of boots and shoes while upon the last, the combination of rounding and channeling knives, and feeding mechanism comprising two members which receive between them the work, means for closing said members on the work to thereby clamp and hold it in place, and means for operating said members to feed along the work, a guiding device for the work, movable freely toward and from the rounding and channeling knives during the rounding and channeling operation, to vary the position of the boot or shoe with relation to said knives, and thereby vary the width of the projecting edge of the sole, said guide being constructed. 120

125

130

and arranged to engage the work close to and directly opposite where the rounding is being done, substantially as described.

5. In a machine for rounding and channeling the soles of boots and shoes while upon the last, the combination with the rounding and channeling knives, of a feeding mechanism, a work-guide shaped and held in position to enter the crease between the welt and upper, 10 and movable freely transversely to the direction of the feed, and mechanism for actuating the work-guide during the operation of the machine, said guide acting upon the work opposite where the rounding is being done, substantially as described.

15 6. In a machine for rounding and channeling the soles of boots and shoes while upon the last, the combination with the rounding and channeling knives, of a feeding mechanism, a work-guide shaped and held in position to enter the crease between the welt and upper, 20 and movable freely transversely to the direction of the feed, and mechanism for actuating the work-guide during the operation of the machine, and a stop for limiting the forward 25 movement of said work-guide, said guide acting upon the work opposite where the rounding is being done, substantially as described.

7. In a machine for rounding and channeling the soles of boots and shoes while upon the last, the combination with the rounding and channeling knives, of a feeding mechanism, a work-guide shaped and held in position to enter the crease between the welt and upper, 30 and movable freely transversely to the direction of the feed, and mechanism for actuating the work-guide during the operation of the machine, and a stop for limiting the rearward 35 movement of said work-guide, said guide acting upon the work opposite where the rounding is being done, substantially as described.

40

8. In a machine for rounding and channeling the soles of boots and shoes while upon the last, the combination with the rounding and channeling knives, of a feeding mechanism, a work-guide shaped and held in position to enter the crease between the welt and upper, 45 and movable freely transversely to the direction of the feed, and mechanism for actuating the work-guide during the operation of the machine, and two adjustable stops between which said work-guide plays, said guide acting upon the work opposite where the rounding is being done, substantially as described.

50 9. In a machine for rounding and channeling the soles of boots and shoes while upon the last, the combination of rounding and channeling knives and means for engaging the work opposite where the rounding is being done and for guiding the work and for moving 55 it transversely to the direction of the feed of the work during the operation of the machine to vary the position of the cut made by said knives, substantially as described.

10. In a machine for rounding and channeling the soles of boots and shoes while upon the last, the combination of rounding and channeling knives and means for guiding the work and for moving it transversely to the direction of the feed of the work during the operation of the machine to vary the position of the cut made by said knives, substantially as described.
